UNITED STATES PATENT OFFICE.

RICHARD GARLAND, OF JUNCTION CITY, KANSAS.

SPRAYER.

Application filed April 11, 1925. Serial No. 22,365.

The present invention relates to a sprayer, and aims to provide a device of this nature on a two wheeled supporting structure which may be pulled by a horse, and which will be convenient in getting the machine through tight places when necessary. The invention also aims to provide a device of this nature which it is easy to pull along a row and to make the sharp turn at the end thereof so as to pull it down the next row.

An important object of the invention is to provide a sprayer of this nature having a pumping mechanism operable by the wheels of the supporting structure so that the solution to be sprayed may be placed in a tank under pressure whereby it may be sprayed from a hose or the like most effectively.

A further important object of the invention is to provide a sprayer of this nature which is exceedingly simple in construction, inexpensive to manufacture, efficient and reliable in operation, strong, durable and not likely to readily become out of order, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:—

Figure 1 is a side elevation of the sprayer embodying the features of my invention.

Figure 2 is a top plan view thereof.

Figure 3 is a longitudinal section through the pump.

Figure 4 is a fragmentary elevation of the low pressure-tank.

Figure 5 is an elevation of a disc rotatable with the shaft.

Figure 6 is an elevation of a ring rotatable with the wheel, and

Figure 7 is a section through one of the check valves.

Referring to the drawing in detail, it will be seen that 5 designates a frame, mounted on the brackets 6, through which extend the crank shaft 7, the ends of which are mounted in wheels 8. A suitable tongue or other draft means 9 extends forwardly from the frame in order that the same may be drawn by horses or the like. A plate 10 is mounted on the forward portion of the frame 5,

and supports a high pressure tank 11. A low pressure tank 12 is mounted on the rear end of the frame being held in place by straps 13 or any other suitable means. A pump cylinder 14 is mounted on the plate 10 immediately below the high pressure tank 11. Pipes 15 lead from the ends of the cylinder 14 to the bottom portion of the high pressure tank 11 and have check valves 16 therein. Pipes 17 connect with the other end of the cylinder 14 and have check valves 18 therein. The check valves 16 allow the passage of fluid from the cylinder 14 only, while the check valves 18 allow the passage of fluid toward the cylinders. The pipes 17 are connected to a coupling 19 connected by pipe section 20 to the low pressure tank 12. A piston 21 is reciprocated in the cylinder 14 by a piston rod 22 extending through the stuffing box at one end of the cylinder 14. This rod 22 extends rearwardly under the frame and its end is slidable through a bracket 24. An arm 25 is fixed rigidly to the piston rod 22 and is pivotally connected to a connecting rod 26 which is operable by the crank of the crank shaft 7. A pipe 28 is extended between the tanks 11 and 12, and has a safety valve 29 mounted therein, the specific structure of which is shown to advantage in Figure 7. A partition 30 is provided in the valve 29 and is provided with a valve seat for receiving the valve disc 31 provided with the stem 32 movable in the pocket 33 of a cap 34. A spring 35 is disposed about the stem 32 and tends to hold the valve disc 31 normally closed. The pump is adapted to deliver to the tank 11 about four times as much fluid as is necessary, and therefore, there will be a considerable overflow going through the pipe 28 which will maintain the safety valve open or partially open, and this overflow fluid will agitate the fluid already in the tank 12 to keep it well stirred up, thereby allowing a considerable economy in the use of the spraying fluid.

The end portions of the axle shaft 7 are provided with grooves 37 and discs 38 are receivable on these axle shafts. The hubs 39 of the discs 38 have bolts 40 threaded therethrough so as to be engageable with the grooves 37, thereby keying the disc to the shaft. The hubs of the wheels 8 carry rings 41 provided with interior teeth 42 which are engageable by the pawls 43 pro-

jecting from the periphery of the discs 38. By loosening up on the bolts 40, the discs may be moved out of the rings and the wheels will be free to rotate without the shaft. However, when the discs 38 are moved into the rings and the bolts tightened up, the crank shaft 7 operates with the wheel, thereby causing reciprocation of the piston 21 in the cylinder 14 and forcing the spraying material from the lower pressure tank 12 into the high pressure tank 11 and placing the same under pressure so that it may be forced through a suitable spraying hose or the like. The safety valve has its spring 35 so tensioned that the liquid will not flow from the high pressure tank to the low pressure tank unless the pressure becomes great enough to overcome the tension of the spring.

It is thought that the construction, operation, and advantages of this invention will now be clearly understood without a more detailed description thereof. It is desired however, to point out that the present embodiment of the invention has been disclosed merely by way of example and that numerous changes in the details of construction, and in the combination and arrangement of parts may be resorted to without departing from the spirit or scope of the invention as hereinafter claimed or sacrificing any of its advantages.

Having thus described my invention, what I claim as new is:—

In a device of the class described, a wheeled structure of the type wherein two wheels are utilized having their axes aligned transversely under an intermediate portion of the structure, a crank shaft fixed to rotate with the wheels and constituting the axle of the wheeled structure, a connecting rod engaged with the crank of the shaft, a pump suspended below the forward end of the wheeled structure, a piston in the pump, a piston rod extending from the piston, a bracket depending from the rear portion of the wheeled structure, said piston rod being slidable through said bracket, a rigid arm depending from the piston rod and engaged with the connecting rod, a pair of tanks on the wheeled structure, one at the forward end thereof, and one at the rear end thereof, means connecting the tanks with the pump in order that fluid may be passed from one to the other and put under pressure in said other, and a pipe connecting the two tanks and having a check safety valve therein for allowing passage of liquid from the tank to which the fluid is forced by the pump when the pressure becomes excessive therein.

In testimony whereof I affix my signature.

RICHARD GARLAND.
